TYPEWRITING MACHINE

Lewis C. Myers, Freeport, N. Y., assignor to Royal
Typewriter Company, Inc., New York, N. Y., a
corporation of New York

Application March 1, 1934, Serial No. 713,571

2 Claims. (Cl. 197—176)

This invention relates to new and useful improvements in typewriting machines generally, although more particularly to a column stop mechanism therefor.

5 Among the several objects of the invention are to provide a very simple and efficient connection between the carriage escapement release mechanism and the column tabulating stop lever whereby upon depression of the tabulator key lever the carriage will be released from its escapement and the carriage stop finger will be moved into operative position to be engaged by the adjacent active column stop.

In the drawings:

10 Figure 1 is a vertical sectional view of a typewriting machine embodying my invention, the escapement rack bar and the stop finger being shown in normal positions.

Figure 2 is a partial rear elevation thereof.

20 Figure 3 is a vertical sectional view thereof showing the escapement rack bar in elevated or released position and also showing the stop finger in operative position.

Figure 4 is a view partly in rear elevation and partly in section, the view disclosing the mounting for the column tabulating stop lever and the pusher finger for the column stop.

25 Figure 5 is a vertical sectional view showing the relation between the column stops and the pusher finger.

Figure 6 is an enlarged horizontal section taken on the line 6—6 of Figure 3.

30 Figure 7 is an enlarged horizontal section taken on the line 7—7 of Figure 3.

Figure 8 is a perspective view of the pusher finger.

35 Figure 9 is a view showing in separated perspectives the link connections between the carriage stop finger and the column tabulating stop lever.

40 Figure 10 is a detail view showing a modified form of my invention.

I have shown my invention as applied to a Royal standard typewriting machine although it will be understood that the invention may be applied to other typewriting machines if desired. This machine includes the usual main frame A which supports a non-shiftable track 2 upon which runs a carriage B having end plates 3, 3 which support a platen 4, the main frame including the usual rear wall 5. An escapement rack bar 6 is attached to the usual frame 6^a which is pivotally supported on the carriage, the rack bar being normally held by a spring 1 in engagement with a pinion 8 mounted on the usual shaft. An escapement wheel 9 which is mounted to rotate

with the pinion 8 cooperates with the usual escapement dog (not shown). Secured to the end plates 3, 3 of the carriage is the usual margin stop bar 10 which is disposed above and slightly in front of the rear wall 5 of the main frame.

Attached to the rear wall 5 by a screw 11 is a bracket C having rearwardly extending arms 12, 13, the latter terminating in an upwardly projecting portion located in rear of and in spaced relation to the margin stop bar 10. A horizontal shaft 14 is mounted in the arms 12, 13 and the usual column tabulating stop lever D is pivoted intermediate its ends on said shaft, the upper arm 15 of the lever extending in rear of the margin stop bar 10, and the lower arm 16 of said lever extending downwardly between the escapement rack bar 6 and the rear wall 5 of the main frame. A rack bar lift lever 17, pivoted at 17^a, is provided with a downwardly extending arm 17^b which is disposed in front of the arm 16 so that when the latter is moved forwardly the arm 17^b will be engaged and the rack bar 6 will be elevated out of engagement with the pinion 8, as shown in Figure 3. Rigidly attached to the lower arm 16 is a laterally extending extension 18. A 20 2-part link 19 is connected at its rear end to the extension 18 and at its forward end to a tabulator key lever E which is pivotally mounted on a transverse rod 20 supported on the main frame A, the key lever E being disposed at the right hand end 25 of the keyboard. A spring 21 is connected to the lever E and to a part of the main frame A, and functions to retain the key lever in its normal position against a stop 22. Thus when the key lever is depressed the column tabulating lever 30 D will be swung about its fulcrum and the rack bar 6 will be disengaged from its associated pinion 8 to thereby release the carriage escapement.

35 Supported by the end plates 3, 3 of the carriage and disposed in rear of the column tabulating stop lever D is a column stop frame which includes upper and lower rack bars 23 and 24. These bars are rectangular in cross section and the lower face of the upper bar is formed with a series of transverse grooves 25 and the upper 40 face of the lower bar is formed with a series of transverse grooves 26, the grooves 25, 26 being arranged in pairs and spaced apart at distances corresponding to letter space intervals. Supported on the stop frame is a series of column 45 stops F, there being one of these stops for each pair of upper and lower grooves 25, 26. In other words, these stops F are mounted on the stop frame at letter space intervals. Each stop F is 50 of H-shaped construction and is swingable in a 55

fore and aft direction and is automatically retained in each extreme position by means of a spring 27 attached to the stop and cooperating with the upper rack bar 23. Thus when the stops 5 are in their forward positions they are inactive whereas when they are in their rearward positions they are active. In order to swing the predetermined stops F outwardly or rearwardly to active positions, there is provided a tabular stop 10 set key G which when depressed causes a pusher finger 28 to be moved rearwardly into engagement with the registering column stop F and thereby swing the latter rearwardly into active position. This tabular stop set key G is located in the key-board at the right hand end thereof and adjacent the tabulator key lever E. The key G is fulcrumed on the cross shaft 20 and is held in its normal position against the stop 22 by a spring 29. This lever includes a rearwardly and upwardly 15 extending arm 30 to which is connected one end of a pull link 31, the other end of said link being connected to one arm of a bell crank lever 32 fulcrumed as at 33 to a lug 34 integral with the side wall of the main frame A. The other 20 arm of the bell crank lever 32 has a loose connection with one end of a lever 35 which is pivoted intermediate its ends as at 36 to the rear wall 5 of the main frame. The other end of the lever 35 is pivoted connected to the lower end of a thrust 25 link 37, the upper end of said link being pivotally connected as at 38 to a forwardly extending arm 39 which is fixed to a hub 40 journaled on the shaft 14 mounted in the bracket C. Fixed to the hub 40 is the pusher finger 28 and therefore this 30 finger together with the hub 40 and arm 39 constitute in effect a bell crank lever. A stop finger 41 is rigidly connected with the arm 39 and is adapted to cooperate with the front face of the rear wall 5 of the main frame as shown in Figure 5 35 to limit the forward movement of the pusher finger 28. A coil spring 42 is connected at one end to the arm 39 and at its other end to the machine frame A and functions to yieldably retain the pusher finger 28 in its normal position with the stop 41 engaging the rear wall of the main frame. Thus when the tabular stop set key G is 40 depressed the bell crank lever 32 will be rocked and through the medium of the lever 35 the thrust link 37 will be elevated and the pusher finger 28 45 will be swung rearwardly to move the associated column stop F from an inactive to an active position, the springs 29 and 42 functioning to return the key G and the associated parts to their normal position upon release of said key by the operator.

A stop restoring device J is pivotally mounted on the upper end of the arm 13 of the bracket C and is normally held out of contact with the column stops F by a spring j. When it is desired 50 to restore the active stops F to their inactive positions, the restoring device J is swung forwardly to successively engage said stops when the carriage is moved in either direction and thereby swing said stops forwardly to their inactive positions.

Also mounted in the bracket C is a horizontal shaft 43 which is located in rear of the rear wall 5 of the main frame. Fulcrumed on this shaft 43 is a hub 44 of a carriage stop finger H which 55 extends upwardly to a point in rear of the column stop frame which is formed by the rack bars 23, 24. Rigidly connected with the hub 44 opposite the stop finger H is an upwardly extending arm 45 having a rearwardly extending ear 46 to which the upper end of a coil spring

47 is connected, the lower end of said spring being connected to a pin 48 fixed to the bracket C. The carriage stop finger H terminates below the shaft 43 in a stop arm or finger 49 which is adapted to cooperate with the bracket C and therefore limit the rearward swinging movement of said finger, the spring 47 normally holding said finger H in its rearmost position. Integral with and extending upwardly from the extension 18 of the column tabulating stop lever D is a stop 10 arm 50 having a rearwardly extending ear 51 as shown particularly in Figures 3, 6 and 9.

An adjustable link I connects the ear 51 with the upper end of the arm 45 whereby when the tabulating key lever E is depressed to release the 15 rack bar 6 from the escapement pinion 8 the carriage stop finger H will be moved into position to be engaged by the column stop F which has been previously moved to its rearward or active position. This link I comprises two short links 20 52 and 53 which are connected for relative longitudinal adjustment. The front end of the link 52 is pivotally connected to the ear 51 by a pivot screw 54 and the link 53 is provided at its rear end with an upstanding integral arm 55 which 25 is pivoted at its upper end to the upper end of the arm 45 by a pivot screw 56. Front and rear elongated openings 57, 58 are formed in the link 52. A clamping screw 59 passes through the front opening 57 and is engaged in a threaded 30 opening in the rear end of the link 53. A guide pin 60 is rigidly secured to the link 53 at the rear end thereof and adjacent the lower portion of the arm 55 of said link. This guide pin 60 has sliding engagement in the opening 58 35 and functions to retain the links 52 and 53 against relative pivotal movement about the clamping screw 59. It will, therefore, be seen that I have provided a link connection between the column tabulating stop lever D and the carriage 40 stop finger H, and that this link connection insures the stop finger H being moved to its operative position whenever the tabulating key lever E is depressed to release the carriage from its escapement mechanism.

In another form of my invention, as shown in Figure 10, I have provided the hub 44 of the stop finger H with an upwardly extending rock arm 61 and to the upper end of this arm I have pivotally connected as at 62 the rear end of an upwardly and rearwardly extending link 63, the lower front end of said link being pivotally connected as at 64 to the swinging frame 6a which supports the rack bar 6. Thus when the tabulating key lever E is depressed the column tabulating stop lever D will be moved, the rack 6 will be disconnected from the escapement pinion 8, and by means of the link 63 the carriage stop finger H will be swung forwardly to its operating position. It will therefore be seen 60 that in this form of the invention, I have provided a positive thrust connection between the rack bar 6 and the carriage stop finger H.

I claim:

1. In a typewriting machine, the combination 65 with a main frame, of a carriage mounted thereon for letter space movements, an escapement mechanism for the carriage including a normally engaged pinion and rack bar, a lever pivoted on the frame for disengaging the rack bar from 70 the pinion, a margin stop bar fixed to the carriage, a margin stop on said bar, a plurality of movable column stops mounted on the carriage in rear of the margin stop bar, the column stops being located at letter space intervals, a stop 75

lever pivotally mounted on the main frame between the margin stop bar and the column stops and normally disposed in the path of movement of the margin stop, a key for operating said stop lever, the rack bar disengaging lever being operated by the stop lever upon depression of the key to release the rack from the pinion, a single carriage stop finger located in rear of the column stops and pivotally mounted on the main frame and normally disposed out of the path of movement of said column stops, and a link directly connecting the carriage stop finger and the stop lever for moving said finger upon depression of said key into the path of the column stop.

2. In a typewriting machine, the combination with a main frame, of a carriage mounted thereon for letter space movements, an escapement mechanism for the carriage including a normally engaged pinion and rack bar, a lever pivoted on the frame for disengaging the rack bar

from the pinion, a margin stop bar fixed to the carriage, a margin stop on said bar, a plurality of movable column stops mounted on the carriage in rear of the margin stop bar, the column stops being located at letter space intervals, 5 a stop lever pivotally mounted on the main frame between the margin stop bar and the column stops and normally disposed in the path of movement of the margin stop, a key for operating said stop lever, the rack bar disengaging 10 lever being operated by the stop lever upon depression of the key to release the rack from the pinion, a horizontal shaft mounted on the main frame, a single carriage stop finger fixed to said shaft and normally disposed out of the path 15 of movement of the column stops, a rock arm fixed to said shaft, and a link directly connecting the rock arm and the stop lever for moving said finger upon depression of said key into the path of the column stop. 20

LEWIS C. MYERS.
